UNITED STATES PATENT OFFICE.

FRANK A. MORIN, OF LEWISTON, MAINE, ASSIGNOR, BY MESNE ASSIGNMENTS, TO
UNIVERSAL WINDING COMPANY, OF BOSTON, MASSACHUSETTS, A CORPORATION
OF MASSACHUSETTS.

WINDING MACHINE.

Application filed December 5, 1922. Serial No. 605,019.

To all whom it may concern:

Be it known that I, FRANK A. MORIN, a citizen of the United States, residing in Lewiston, in the county of Androscoggin 5 and State of Maine, have invented an Improvement in Winding Machines, of which the following description, in connection with the accompanying drawings, is a specification, like characters on the drawings representing like parts.

This invention relates to winding machines for winding yarn upon yarn receivers.

Heretofore it has been the general practice to dye yarn in the chain and then wind it upon yarn receivers or bobbins by a quilling machine for subsequent use in the loom. It has also been suggested heretofore that the yarn could be wound into a package and 15 then dyed by forcing the dye material into the wound yarn package. Yarn whether dyed in the chain or in the wound package usually carries with it or projecting from it small portions of fibre which become detached from the yarn during its subsequent winding operation onto the yarn receivers, and accumulate on the yarn guiding means or other parts of the machine and are either carried along with the yarn in undesirable 20 bunches or effect a discharge of the yarn itself from the yarn guiding and tensioning means.

The object of the present invention is to provide a winding machine for winding 25 yarn upon yarn receivers or bobbins in which the objectionable accumulation of lint on the yarn guiding means or other parts and the disturbances of the yarn with relation to the yarn guiding means or tensioning devices are entirely obviated; and while the 30 advantages of the invention are more manifest in connection with dyed yarn, the invention may be advantageously employed in connection with winding other kinds of 35 yarn and are also observable in winding machines of any general character such as spooling or other machines.

The novel characteristics and new combination of parts will be made clear from 40 the following description and the accompanying drawings of one good form of winding machine embodying the present invention.

In the drawings:

Fig. 1 is a perspective view of a winding

machine containing the present invention, only sufficient portions of the machine being shown as are necessary to make clear the invention and its mode of operation;

Fig. 2 is a sectional view through one of the yarn packages, and its rotatable support; and

Fig. 3 is a sectional view of one form of yarn engaging and clearing means between the yarn supply and the receiver on which the yarn is to be wound.

The machine which has been selected for the present explanation of the invention is designed to wind the yarn by filling wind upon the yarn receivers or bobbins and represents in general the ordinary spinning frame modified to embody the present invention, but as hereinbefore noted, the invention is not necessarily limited to such machine but may be advantageously employed 70 in other machines for winding yarn upon yarn receivers, such, for instance, as spoolers and the like.

The machine frame as shown comprises the end members 1 which are joined by cross 80 pieces 2 which in the present illustration constitute what is commonly known as a spindle rail. The spindle rail 2 has mounted thereon the spindles 3, each of which carries a yarn receiver or bobbin 4, as usual. The 85 spindles and yarn receivers or bobbins are rotated, as usual, by suitable bands 5 driven from the usual cylinder or tin roller 6.

The ring rail 7 is connected by the rods 8 with the usual yarn builder mechanism 90 which serves the purpose of raising and lowering the ring rail to direct the yarn upon the yarn receivers. The ring rail 7 has mounted thereon the rings 9 and associated with each ring is a fixed yarn guide 10, the 95 purpose of which is to guide the yarn from a fixed point upon the ring rail 7 to the yarn receiver with which it is associated.

Extending between the frames 1 of the machine is a top frame 11 on which is 100 mounted for rotative movement a series of supports 12 for the wound yarn packages 13. As more clearly indicated in Fig. 2, each of the supports 12 is mounted for rotative movement on the top frame 11 by a bearing 105 14, and extending upwardly from each of the supports 12 is a stud or centering device 15.

Where the yarn is dyed in the wound package, as indicated in Fig. 2, the core of the 110

package is formed by a spring 16 over which is placed a piece of fabric 17, the construction being such that the dye may be forced inwardly or outwardly through the wound 5 yarn on the core 16.

Each of the supports 12 on which the yarn package is supported is given rotative movement in order to facilitate unwinding of the yarn from the supporting yarn package. 10 This is particularly desirable when the yarn which is to be wound upon yarn receivers or bobbins 4 is dyed, and the utility of rotating the yarn package manifests itself during the unwinding of the package as the yarn will 15 not hang or cling to or stick upon the package, but will be presented in proper position by the rotation of the package for the yarn to be drawn or pulled therefrom.

Any suitable means may be employed for 20 rotating the yarn packages, but in the present instance of the invention each of the supports 12 is provided with teeth 18 which are engaged by worms 19 on the worm shafts 20 which, as shown, are mounted for rotative movement in bearings 21 carried by the top frame 11. The worm construction for rotating the supports 12 constitutes a good practical form of support rotating means but it is obvious that the supports 12 30 may be otherwise slowly rotated upon the top frame 11.

Each of the worm shafts 20 is provided with a sprocket wheel 22 about which passes a sprocket chain 23. The sprocket chain 23, 35 as shown, passes over a sprocket wheel 24 mounted upon a shaft 25, and the shaft 25, as shown, is provided with a gear 26 which derives motion through a train of gearing 27, 28 from a gear 29 driven by a going 40 part of the machine.

Arising from the machine frame are uprights or supports for an overhead frame or guide, and in the present instance one of said uprights is shown having adjustably secured 45 thereto by a set screw 31 the yarn guide frame 32.

The yarn guide frame 32 has its side portions provided with shaft supporting brackets 33, one at each side of the machine, 50 and each bracket has a bearing 34 in which is mounted the rotatable shaft 35 which receives its rotative movement through the sprocket chain 36 passing over a sprocket wheel 37 fixed to the shaft 35 and operated 55 from the sprocket wheel 38 mounted on the rotating shaft 35.

Secured to the rotating shaft 35 are a series of yarn engaging devices which serve to draw the yarn from the yarn packages 60 13 and deliver it under a proper tension to the yarn receivers 4.

As more clearly indicated in Fig. 3, each of the yarn engaging devices on the shaft 35 consists of two members or flaring disks 65 39, one of which is secured to a hub portion

40 fixed to the shaft 35 by a set screw 41. The opposing member or flared disk 39 is mounted on an extension 42 of the hub 40 and is normally pressed towards the companion disk 39 by a spring 43, one end of 75 which rests against the disk, as shown in Fig. 3, and the other end of which bears upon a collar or nut 44 threaded to the extension 42 of the hub, a lock-nut 45 serving to hold the parts with a spring under adjustable 80 tension. From the construction described it will be apparent that as the shaft 35 is positively rotated, the several yarn engaging devices comprising in the present instance the disks 39, will rotate therewith.

The yarn *a* is led from the yarn packages 13 over suitable yarn guides 46 carried by the guide frame 32 and then between the disks 39, without, however, passing completely around the shaft 35. In other words, 85 the yarn passes between the disks 39 on its way from the yarn package to the yarn receiver and is positively drawn from the yarn package by the grip thereon between the disks 39, the effect being that the yarn 90 will be delivered to be wound upon the yarn receivers under appropriate tension, and the accumulation of lint between the disks 39 will be obviated, so that the yarn itself will not be pushed outwardly from the 95 bight between the disks. Any lint that may be detached from the yarn will fall away from between the disks as they rotate, and the grip of the disks upon the yarn will remain undisturbed. The positive rotation 100 of the yarn engaging devices by the shaft 35 also tends to smooth the yarn and lay any projecting fibres close to the yarn, the timed rotation of the disks being such that they not only draw the yarn from the yarn 105 package but deliver it to the yarn receiver under appropriate tension.

As indicated in Fig. 1, it will be noted, 110 that the yarn *a* after being delivered by the rotating yarn engaging devices passes under the looped portion of the fixed yarn guide 10 and from there directly to the yarn receiver or bobbin on which the yarn is to be wound.

What is claimed is:

1. In a machine for winding yarn without twisting upon a yarn receiver from a wound yarn package, the combination of a support for a wound yarn package, a yarn receiver to which the yarn is to be delivered without additional twist being imparted thereto, means for rotating the yarn receiver at a predetermined speed, a fixed guide at the side of and for directing the yarn to the rotating yarn receiver without twist, means for rotating the wound yarn package at a slower rate of speed than that of the yarn receiver, and a yarn guide for the wound yarn package for causing the 120 125 130 yarn to be drawn endwise from the wound

- yarn package as it is slowly rotated for delivery through the fixed yarn guide at the side of the more rapidly rotating yarn receiver. 60
2. In a machine for winding yarn without twisting upon yarn receivers from wound yarn packages, the combination of supports on which the wound yarn packages are mounted in upright position, yarn 65 receivers also mounted in upright position to which the yarn is delivered without additional twist, fixed yarn guides at the side of the upright yarn receivers for directing the yarn thereto, means for rotating the yarn 70 receivers at high speed, means for rotating the upright wound yarn package supports at a lower rate of speed, and yarn guiding means above the upright wound yarn packages for causing the yarn to be delivered upwardly and endwise from wound yarn 75 packages without snarling as the packages are slowly rotated relatively to the rotation of the yarn receivers. 80
3. In a machine for winding yarn upon yarn receivers, the combination of a support for the yarn receivers sustaining them in upright position, a rail movable lengthwise of the yarn receivers, yarn guides mounted in fixed position on the rail at the side of the receivers for directing the yarn thereto without causing additional twist, means for rotating the upright yarn receivers at high speed, a series of rotating supports on 85 which wound yarn packages are mounted in upright position for rotative movement therewith, a shaft extending past the rotating supports of the wound yarn packages, driving connections between the shaft and rotating supports, means for rotating the shaft to impart rotating movement to the wound yarn package supports at a slower rate of speed than that of the yarn receivers, and yarn guiding means above the upright wound yarn packages to cause the 90 yarn to be delivered upwardly from the wound yarn packages without snarling as they are slowly rotated. 95
4. In a machine for winding yarn without twisting upon yarn receivers from wound yarn packages, the combination of supports on which the wound yarn packages are mounted in upright position, yarn receivers also mounted in upright position to which the yarn is delivered without additional twist, fixed yarn guides at the side of the upright yarn receivers for directing the yarn thereto, means for rotating the 100 yarn receivers at high speed, means for rotat-
- tating the upright wound yarn package supports at a slower rate of speed, yarn guiding means above the upright wound yarn packages for causing the yarn to be delivered upwardly and endwise from wound yarn packages without snarling as the packages are slowly rotated relatively to the rotation of the yarn receivers, and a series of rotating yarn engaging devices between the yarn guiding means above the wound yarn packages and the fixed yarn guides which deliver the yarn to the yarn receivers. 105
5. In a machine for winding yarn without twisting upon yarn receivers from wound yarn packages, the combination of supports upon which the wound yarn packages are mounted in upright position, yarn 110 receivers also mounted in upright position to which the yarn is delivered without additional twist, fixed yarn guides at the side of the upright yarn receivers for directing the yarn thereto, means for rotating the yarn receivers at high speed, yarn guiding means above the wound yarn packages for causing the yarn to be delivered endwise from the wound yarn packages, a series of yarn engaging devices between said yarn guiding means and fixed yarn guides at the side of the receivers, means for rotating the wound yarn packages and yarn engaging devices at a slower rate of speed than that of the receivers that yarn may be withdrawn endwise from the wound packages and delivered to the receivers without snarling. 115
6. In a machine for winding yarn upon yarn receivers, the combination of supports for the yarn receivers sustaining them in upright position, a rail movable lengthwise of the yarn receivers, yarn guides mounted in fixed position relative to the rail at the side of the yarn receivers, means for rotating the yarn receivers at a predetermined speed, a series of supports on which wound yarn packages are mounted in upright position, a shaft having a series of gears for rotating the series of supports and wound yarn packages mounted thereon, means for driving said shaft to cause the supports and wound yarn packages to be rotated at a slower rate of speed than the yarn receivers, and yarn guiding means located above the wound yarn packages to cause the yarn to be directed lengthwise of the wound yarn packages without snarling as they are slowly rotated. 120

In testimony whereof, I have signed my name to this specification.

FRANK A. MORIN.
